WILLIAM BUFORD HILL, OF TUCUMCARI, NEW MEXICO.

STATION-INDICATOR.

1,044,385.

Specification of Letters Patent.

Patented Nov. 12, 1912.

Application filed June 11, 1910. Serial No. 566,345.

To all whom it may concern:

Be it known that I, WILLIAM BUFORD HILL, a citizen of the United States, and a resident of Tucumcari, in the county of 5 Quay, State of New Mexico, have invented certain new and useful Improvements in Station-Indicators, of which the following is a specification.

My invention is an improvement in station indicators, and consists in certain novel constructions and combinations of parts hereinafter described and claimed.

The object of the invention is to provide a device of the character specified, operated 10 automatically by fluid under pressure or the like, and actuated either from the motor or the axle of the car, or from an independent wheel running on the rail.

Referring to the drawings forming a part 20 hereof: Figure 1 is a vertical section of the improvement; Fig. 2 is a plan view of the mechanism; Fig. 3 is a section on the line 3—3 of Fig. 2; Fig. 4 is a side view of the trolley tripping mechanism; Fig. 5 is a front 25 view of Fig. 4; Fig. 6 is a sectional view of the tripping mechanism; Fig. 7 is a sectional view of one end of the cylinder, and Fig. 8 is a detail sectional view of the reversing mechanism.

30 The embodiment of the invention shown in the drawings is mounted in a casing 1, which is adapted to be supported in a suitable position in the car, and is provided in its side wall with an opening 2, through 35 which the announcements appear, the opening being covered by a sheet 3, of transparent material, preferably lens shaped and convex as shown, so that the announcement will appear magnified.

40 A roll 4 is journaled behind the opening, being secured on a transverse shaft 5, journaled in the walls of the casing. Upper and lower rolls 6 and 7 are secured on shafts 8 and 9 journaled in the walls of the casing 45 behind the shaft 5, and the strip 10 on which the announcements or indications are printed has its ends secured to, and winding on, the rollers, the intermediate portion passing over the roller 4, which is arranged between the rollers 6 and 7. The strip passes 50 from the roller 6 over the roller 4 to the roller 7, during the passage of the car in one direction and reversely for the return trip, and the stations are printed on the strip in regular order and are visible 55 through the lens 3. Each of the shafts 5, 8

and 9 has secured thereto a ratchet wheel 11, 12 and 13, respectively, and the wheels are operated by means of a piston 14, moving in a cylinder 15 and moved by the motor fluid. 60 The piston rod 16 of the piston extends through a stuffing box 17, in the head 18 of the cylinder, and the upper end of the rod extends through a guide block 19, secured to the casing near its upper end. A cross 65 arm 26 is secured transversely of the rod below the guide block, the rod passing through an opening in the arm and being nearer one end of the arm than the other, and a spring 20 encircles the rod between 70 the guide block and the cross arm and acts normally to press the arm downwardly.

A link 21 is pivoted to the arm on each side of the piston rod, as at 22, and a pair of levers 23 is journaled at one end on the 75 shaft 5, and provided at the other with a pivotally connected pawl 24 and 25, respectively, the lower end of each link being pivoted to the adjacent lever intermediate its ends. Both pawls engage the ratchet 80 wheel 11, the pawl 24 driving it in one direction and the pawl 25 in the other. The long end of the cross arm 26 is provided with an opening through which extends the reduced portion 27 of a rod 28, a shoulder 85 29 being formed between the reduced portion and the main portion, upon which the cross arm rests, and a spring 30 encircles the reduced portion between the end of the cross arm, and a washer 31, through which 90 the end of the rod passes. A lever 32 is journaled by one end on the shaft 8, and is provided at its opposite end with a pivoted pawl 33, which engages the ratchet wheel 12.

A lever 34 is journaled intermediate its 95 ends on the shaft 9, and a link 35 connects one end of the lever with the lever 32, being pivoted to the said lever between the pawl and the shaft, and the rod 28 is pivoted to the opposite end of the lever 34. Outside 100 of the rod a pawl 36 is pivoted to the lever 34 and engages the ratchet wheel 13. Each of the pawls 24 and 25 is pivoted by one end to the lever and is held in engagement with the ratchet wheel by a spring 37, one 105 end of which engages the pawl and the other is formed into a collar 38 encircling the head 39 of a link 39^a to be presently described.

A collar 40 is journaled on each of the shafts 8 and 9 and each collar is provided 110 with two radial lugs 41 and 42. A spring 43 is pivoted to each of the lugs 41 by one

end and the other is pivoted to the adjacent pawl 33 or 36, and the arms 42 of the collars are connected by a link 44. The pawl 33 is pivoted to the lever 32 by its center, one end of the pawl engaging the ratchet wheel and the other being engaged by the spring at 45, while the pawl 36 is pivoted to the lever 34, by one end, the other engaging the ratchet wheel, and the spring being connected to the center of the pawl, as at 46. The link 44 is provided with spaced collars 47, each engaging one end of a spring 48, the springs encircling the link between the collars, and the collars are held against the springs by bolts 49. A three armed rock shaft 50 is journaled in the casing between and behind the rollers 6 and 7, one of the arms 51 extending forwardly and being provided with an opening through which extends the link 44, and a spring 48 is arranged on each side of the arm. Another arm 52 of the rock shaft is pivoted to one end of the link 39^a before mentioned, the other end of which is provided with the head 39, encircled by the collars 38 of the springs 37, and the head is provided with a slot or elongated bearing 53, through which the shaft 5 passes. The third arm 54 of the rock shaft extends downwardly and is provided with a knob 55 journaled thereon by a pin 57, and extending through a slot 56, in the case. The slot is provided with three notches 56^a for engagement by the knob, and the knob is engaged by a spring 58 to hold it in place in the notches.

The springs 37 and 43 are heavy wire, as shown, and are more properly operating means for the pawls than springs, since their movement swings the pawl into and out of engagement with the respective ratchet wheels. They are, however, sufficiently resilient to hold the pawls to their work, while permitting the pawl to slip idly over the teeth of the ratchet wheels on the return stroke.

As before stated, the pawls 24 and 25 drive the roller 4 in opposite directions, and when one is in engagement with the wheel the other is necessarily out of engagement. The rock shaft 50 is the reversing mechanism for the pawls, and operates as follows:—When the rock shaft is in the position shown in Fig. 1, the pawl 25 is in engagement with the ratchet wheel 11, and the roller would be turned anti-clockwise. The lower roller is now the winding up roller and the upper roller the unwinding roller. When the piston moves upward, the springs 20 and 30 are compressed and the pawl 25 moves the ratchet wheel 11 and roll 4. The rod 28 is also moved upward, and the roller 7 is rotated clockwise and the roller 6 is not affected. On the down stroke the pawls 25 and 36 slip idly over the teeth of the ratchet wheels, and the pawls 24 and 33 are

out of engagement. Every complete stroke of the piston will move the rollers 4 and 7 positively. When it is desired to reverse the direction of travel of the strip 10, the rock shaft 50 is swung to move the link 44 upwardly and the link 39^a to the right of Fig. 1. The pawl 25 is now swung out of engagement with the ratchet wheel 11, and the pawl 24 into engagement therewith, and the position of the pawls 33 and 36 is reversed, the pawl 33 being engaged with the ratchet wheel and the pawl 36 disengaged. It will be clearly evident that under these circumstances the strip will travel in the opposite direction, for the roller 4 will now travel clockwise, and the roller 6 will be the winding up roller. The strip is engaged above and below the opening 2 of the casing by rollers 59 which hold it against the face of the roller 4.

The device is, as before stated, operated by compressed air, and the displaying mechanism just described may be operated by trips arranged preferably on the trolley wire at points where announcements are to be made, or it may be operated by mechanism driven by the movement of the car, which mechanism will actuate the displaying mechanism at the proper intervals. The latter operating means is shown in Figs. 2 and 3 and comprises a casing 60^a, on the side of which is journaled a sprocket wheel 60 which is adapted to be connected by a suitable chain with a rotating part of the car. A worm 62 is secured on the shaft of the sprocket wheel inside the casing, and meshes with a worm wheel 63, on a vertical shaft 64, journaled in bearings 65, on the casing. The lower end of the shaft is provided with a pinion 66, which meshes with a gear wheel 67 on a counter shaft 68 journaled in bearings 69. The upper end of the countershaft is provided with a bevel pinion 70, which is adapted to mesh with one of two bevel gear wheels 71, and 72, secured to a shaft 73, journaled transversely of the casing in the walls thereof.

The shaft 73 has secured thereto a drum 74, and on the other side of the drum from the bevel gear wheels the shaft is provided with a sprocket wheel 75, connected by a sprocket chain 76, with a sprocket wheel 77 on a parallel screw shaft 78, also journaled in the casing, and provided intermediate its ends with a thread 79. The peripheral surface of the drum is provided with a spirally arranged radial flange or rib forming a continuous cam wheel 80, the flange being provided at irregular intervals with recesses or notches 81. The arrangement of the notches corresponds to that of the announcements or stations, and the distance between the notches is proportional to the distance between the stations. The length of the cam is in proportion to the length of the

strip and the length of the route, so that the roller to be described will travel from one end of the flange to the other, while the car is traveling from one end of the route to the other.

A sleeve nut 82 is mounted on the screw rod 79, and the nut is provided with an upwardly extending arm 83 having at its end an angular portion 84, on which is journaled a flanged roller 85 which engages the cam. The relation between the sprocket wheels 75 and 77 is such that the nut moves with the arm 83 always opposite the flange and with the roller in engagement therewith, and the arm is pressed toward the cam by a plate spring 86 secured at one end to the casing, as at 87, and engaging the arm with its other end. The sleeve nut 82 is provided with two depending side arms 88 which are connected by a cross plate 89, whose lower edge is curved outwardly, as at 90, and the said edge is engaged by a catch 91, on one arm of an elbow lever 92 pivoted between a pair of ears 93, on a link 94, to be described, and the other arm 95 of the elbow lever extends into position for engagement by the nose 113 of a curved lever 97 pivoted on a bracket 98 extending from a cylinder 99 in the casing. The cylinder is provided with a piston 100 and the rod 101 of the piston moves in a tube 102 extending into the cylinder from one end. A coil spring 103 encircles the tube and rod, normally pressing the piston toward the end of the cylinder remote from the curved lever. The lower end of the curved lever 97 is in position for engagement by the rod when the piston is moved against the resistance of the spring, and when so engaged, the nose 104 of the lever is moved into engagement with the arm 95 of the elbow lever, which in turn is moved to release the cross plate 89. The inlet 104 of the cylinder is at the end remote from the curved lever 97 and is controlled by a valve 105, whose stem 106 is pivoted to one end of a lever 108 pivoted to a bracket 109 on the cylinder. The opposite end of the lever is pressed upwardly by a spring 110 secured to the cylinder and is provided at its extremity with a notch 111. The link 94 before mentioned, is also provided at its lower end with a roller 94^a normally resting in a notch 111^a above the notch 111. The valve 105 closes the inlet 104 by its upward movement and opens it by its downward movement, and when the rod 101 of the piston engages and swings the curved lever 97 the valve is closed by the engagement of the lug 112 with the adjacent end of the lever.

The admission of fluid under pressure to the cylinder 15, Fig. 1, is controlled by a three-way valve 150. The said valve is connected to the upper end of the cylinder by a pipe 151, and to the lower end of the cyl-

inder by a pipe 152. The valve is connected to a source of air supply by a pipe 150^b, and is provided with an exhaust port. The valve is operated by an arm 152^a extending laterally from the sleeve 154 secured to the piston rod 16. The said arm is provided with an angular portion 153 having a sleeve 155 slidable on the link 156 secured to the stem 157 of the valve. The sleeve is slidable between collars 155^a on the link, and the collars are so arranged that the sleeve 155 will engage one of the collars near each end of the travel of the piston, so that the valve 150 will not be shifted until just before the piston has finished its travel. The upper end 158 of the cylinder 15 is connected by a pipe 158, with the inlet pipe 104 of the cylinder 99.

The operation of the mechanism above described is as follows:—When the roller 85 engages a depression 81 in the cam 80, the lever 83 swings on the screw shaft, the upper end thereof being forced inwardly by the spring 86 and the said spring is of sufficient width to engage the lever whatever its position. When the upper end of the lever swings as above described, the link 94 is carried with the lower end of the lever, and the roller 94^a is dislodged from the notch 111^a, dropping into the notch 111. This movement of the roller 94^a permits the adjacent end of the lever 108 to be pressed upward by the spring 110, thus depressing the opposite end of the lever and opening the valve 105. The opening of the valve 105 permits the air above the piston 14 to exhaust through the pipe 158 into the cylinder 99 and the piston 100 in the said cylinder 99 is moved to the left of Fig. 3 by the in-coming air. The valve 150 is normally in the position shown in Fig. 1, that is, in the position to connect the lower end of the cylinder 15 with the source of fluid under pressure. The piston however has not moved because the pressure below the piston is counter-balanced by the air above the piston and the spring 20. When however, the valve 105 has been opened as above mentioned, the air pressure below the piston 14 forces the said piston upward, and drives the air from above the piston 14 into the cylinder 99. The piston 14 moves upward, operating the display mechanism, and when near the end on its upward stroke, the valve 150 is reversed, to connect the upper end of the cylinder 15 with the source of fluid under pressure and to connect the lower end with the atmosphere. The piston 14 is then forced downward, returning all the parts to their original position. The movement of the piston 100 to the left end of the cylinder 99 causes the rod 101 to engage the tail of the lever 97 and swings the said lever on its pivot. When the lever 97 is swung as above mentioned the lug 113 engages the arm 95

of the elbow lever 92, and swings the elbow lever to release the lever 83 from the link 94. The same movement of the lever 97 causes the lug 113 to push the lower end of the link 94 to the right, and to move the roller 94^a from the notch 111 to the notch 111^a. This movement of the link closes the valve 105, and the spring 103 returns the piston 100 to its original position, the air 10 on the opposite side of the piston from the spring being forced out through the bleed vent 106^a in the valve stem 106, Fig. 7. The lug 112 of the lever 97 assists the replacement of the roller 94^a in the notch 111^a by 15 engaging and depressing the adjacent end of the lever 108. As the roller 85 passes out of the depression in the cam 80 the lower end of the lever 83 is swung to the right of Fig. 3 and into engagement with 20 the catch on the arm 91 of the elbow lever 92, and the spring 91^a holds the latch in engagement with the lever.

Where the car is run around a loop or turned at the end of the run it is necessary 25 to reverse the motion of the drum at each end of the run, and in Figs. 2 and 3 this reversing mechanism is shown. A shaft 114 is journaled adjacent to the screw shaft, and the upper end of the link 94 is journaled on 30 this shaft, as are also a pair of spaced arms 115. The arms extend toward the shaft 68 and are connected near the shaft by a cross bar 116. One of the bearings 69 of the said shaft is on this bar, and the bearing is somewhat enlarged to permit some lateral movement of the shaft without bending. Each arm is provided with a lug 117 extending above the shaft 114 in position for engagement by the nut 82 at each end of its travel. 35 A spring arm 160 extends inwardly from the wall of the casing, and the shaft 68 is provided with a rigid collar 161, and a loose collar 162 above the rigid collar and next to the spring arm. The collar 162 is provided 40 with a beveled projection 163 on its upper face on each side of the shaft, and the arm is provided with a similar projection 164 on its under face. A pin 165 is secured to the collar 162 and extends through a slot in the arm 160, and the said arm is also traversed by the shaft 64.

The bearing 69 is slidable in a vertical opening in the cross bar 116 and is engaged on each side by a spring 166. A collar 162 55 is secured to the shaft 68, and a second collar 164 is journaled on the shaft above the collar 162. The collar 164 is provided with oppositely arranged upwardly extending beveled projections 165, one on each side 60 of the shaft 68. The said projections are adapted for engagement with the projections 163 of similar shape, on a resilient arm 160 secured to the wall of the casing, and having openings for receiving the shafts 64 and 68. A pin 167 extends upwardly

from the collar 164, and passes through a slot in the arm 160.

As the roller 85 travels on the rib, the sleeve nut 82 is shifted in one direction until it engages one of the lugs 117. For 70 instance, in Fig. 2, if the sleeve nut is moving toward the left of the said figure, it will finally engage the lug 117 at the left of the said figure, and will shift the arms 115 of which the lugs are a part. The 75 spring arm 166^a holds the shaft 68 in the position shown, by the inter-engagement of the lugs 163—165. As soon however, as the lug 117 is engaged as above specified, sufficient pressure is brought to bear on the 80 frame to swing the shaft 68, and the spring arm is lifted, the lugs 165 engaging the opposite sides of the lugs 163 and the pinion 70 engaging the gear ring 72. By this arrangement any possible stripping of the 85 teeth is prevented when engaging or disengaging. The engagement of the nut with the lug moves the frame composed of the arms and cross bar and swings the shaft 68 slightly, but enough to disengage it from 90 one of the bevel gears 71, 72 and engage it with the other, thus reversing the direction of rotation of the drum.

When it is desired to operate the displaying mechanism by a trip, arranged on the 95 trolley wire, cam rods 118 are arranged in pairs at the points where announcements are to be made, one rod on each side of the trolley wire 119. The rods are connected by U-shaped hangers 120 at each end and 100 at the center of the rods, which extend above and over the wire, and are supported above the wire by braces 121. The cam rods are spaced apart sufficiently to permit the passage of the trolley wheel 112, and 105 a long roller 123 is journaled in the arms of a fork 124 pivoted between a pair of arms 125 on a split collar 126 on the trolley pole 127. The arms 125 are provided at 110 their upper ends with angular portions 128, between which the fork moves, and the angular portions are connected by rivets 129, which act as stops to limit the movement of the fork, and the lower end of the fork is provided with a lateral lug 130, 115 which is connected to a tripping device, to be described, by a link 131. A cylinder 132 is secured on the pole 127 by brackets 133, and a piston 134 is movable in the cylinder. The piston is provided with a rod 135 which 120 moves in a tube 136 extending inwardly from the upper end of the cylinder, and the tube and rod are encircled by a coil spring 137, which normally retains the piston in the position shown in Fig. 6. A rod 138 is 125 slidable in bearings 139 in the brackets, and the angular end 140 is in position for engagement by the piston rod as the piston moves upward. The lower end of the rod 139 is pivoted to a catch 142 pivoted on 130

the cylinder at 143. A lever 144 is pivoted to a lug 145 on the cylinder, and the free end of the lever is adapted for engagement by the catch to hold the lever in a specified position. An inlet pipe 146 is provided for the cylinder, and a valve 147 co-operates with a valve seat in the pipe, the valve being connected by a link 148 with the lever before mentioned. When the roller 123 engages the cam rods 118, the fork is swung on its pivot, and the free end of the lever 144 is swung toward the cylinder, opening the valve, the end of the lever engaging beneath the catch, which engages the lever and holds the valve open. The fluid under pressure now passes into the cylinder, moving the piston against the resistance of the spring until the piston rod engages the angular portion of the rod 139 and moves the same. The movement of the rod swings the catch and releases the lever, and the fluid operating against the valve closes it.

It will be observed that the tripping cylinder just described is substantially the same as that shown in Figs. 2 and 3, the former being operated from the trolley wire and the latter from a rotating part of the car, or by an independent wheel, and when one is used the other will be dispensed with.

The operation of the tripping mechanism shown in Figs. 4, 5 and 6 is substantially the same as that shown in Figs. 2 and 3, it being understood that the pipe 146 in this instance is connected with the pipe 158 of the cylinder 15 and that when the valve 147 is opened, the air exhausts from the upper end of the cylinder 15, to operate the shifting mechanism. As soon as the rod 135 engages the end 140 of the rod 139 the valve is released, and the spring 137 releases the piston 134, the stem of the valve having a bleeding vent.

The shaft 5 is provided with a wheel 171 of polygonal periphery on the opposite side from the ratchet wheel, and a roller 172 engages the said periphery. The roller is journaled in one end of a loop 173, of resilient material, whose other end is journaled on a pin 174, and one of the sides 50 of the loop is engaged by a second pin 175, so that considerable yielding pressure is brought to bear on the roller.

The object of the roller is to steady the motion of the shaft 5, and to take up the jar. The rollers carrying the strip are preferably rubber covered, and the rod 27-28, and the spring 30 is intended to compensate for the different sizes of the holding rollers during the winding of the strip. The tension of the spring may be adjusted by the washer 31. The tension of the springs 48 may also be varied by moving the bolts in the slots shown.

The spring 20 assists in gradually depressing the piston, and also eliminates any jar

in its upward movement. The tripping mechanism shown in Figs. 2 and 3 operates in accordance with the mileage actually covered by the displaying apparatus, while that shown in Figs. 4, 5 and 6 is independent of the actual travel of the car.

Means is provided for varying the moment at which the reversing of the movement of the drum will take place, that is, to correspond with the length of the rib on the drum. The frame consisting of the arm 115, the connecting bar 116, and a sectional plate 180 connecting the arms 115 adjacent to the shaft or rod 114, may be increased or decreased in size. The bar 116 is sectional as is also the plate 180 and the sections of both the bar and the plate are provided with slots 181 at their lapping ends. Set screws 182 extend through the slots for clamping the sections together. It will be obvious that by loosening the set screws the arms 115 may be moved on the rod or shaft 114. When the lugs 117 are moved nearer together, the sleeve nut 82 will engage the said lugs at an earlier point in its travel.

What I claim is:

1. The combination with the car, of a station indicator comprising a casing supported in the car and having a display opening, winding rollers above and below the opening, a roller behind the display opening between the said rollers, a strip of fabric material having printed thereon the names of the stations in regular order winding on the winding rollers, and passing over the display roller, a ratchet wheel secured to each roller, a pawl engaging the ratchet wheel of each winding roller, means including a link connecting the said pawls, a pair of oppositely arranged pawls engaging the ratchet wheels of the display roller for driving it in opposite directions, a three armed rock shaft journaled in the casing, means connected with one arm for oscillating said shaft and extending outside of the casing, means for simultaneously moving the last named pawls in opposite directions to engage one and disengage the other from the ratchet wheel of the display roller, a connection between said means and another arm of the rock shaft, a spring connected with each pawl of the winding rollers, means including a link connecting said springs for simultaneously moving the pawls in opposite directions, the third arm of the rock shaft having an opening through which the link extends, a spring on each side of the arm, and a bolt adjustable on the link at the outer end of each spring, fluid operated means connected with the pawls for operating the rollers, and means controlled by the movement of the car for operating said means at predetermined intervals.

2. In a device of the character specified, a display roller, a pair of winding rollers, a

- strip of material having the station designations in regular order winding on the winding rollers and passing over the display roller, a ratchet wheel connected with each 5 roller, a pawl for the ratchet wheel of each winding roller, a pair of oppositely arranged pawls for the ratchet wheel of the display roller, means for simultaneously moving said pawls in opposite directions, 10 means for simultaneously moving the first-named pawls in opposite directions, a single means for operating both of the said moving means, and a yielding connection between operating means and the moving means of 15 the pawls for the winding rollers.
3. In a device of the character specified, a pair of winding rollers, a display roller between the winding rollers, a strip of flexible material having station designations, 20 winding on the winding rollers at its ends and passing over the display roller, a shaft for each roller, a ratchet wheel connected with each shaft, a pawl for operating the ratchet wheel on each winding roller, a link 25 arranged transversely of the shaft of the display roller and having a circular head provided with a slot through which the shaft extends, a collar encircling the head, a pair of oppositely arranged pawls for engaging 30 the ratchet wheel of the display roller, a connection between each pawl and the collar for simultaneously engaging one pawl and disengaging the other when the link is moved longitudinally, means for simultaneously 35 moving the pawls of the winding rollers to engage one of the said pawls and to disengage the other, and a common means engaging the link and the said pawl moving means for simultaneously operating the 40 same.
4. In a device of the character specified, a pair of winding rollers, a display roller between the winding rollers, a strip of flexible material having station designations, 45 winding on the winding rollers at its ends and passing over the display roller, a shaft for each roller, a ratchet wheel connected with each shaft, a pawl for operating the ratchet wheel on each winding roller, a link having a longitudinal slot for receiving the shaft of the display roller, pawl arms journaled on the display roller shaft and extending at an angle to each other, a pawl on each arm, 50 said pawls being oppositely arranged for moving the ratchet wheel in opposite directions, a connection between each pawl and the link for alternatively moving the pawls into and out of operative position when the 55

link is moved transversely of the shaft, 60 means connected with the pawls of the winding rollers for moving them in opposite directions to alternatively engage and disengage them from the respective ratchet wheels, a common means engaging the link 65 and the said pawl moving means for operating them simultaneously, and a yielding connection between the said common means and the pawl moving means.

5. In a device of the character specified, a pair of winding rollers, a display roller between the winding rollers, a strip of flexible material having station designations, winding on the winding rollers at its ends and passing over the display roller, a shaft 70 for each roller, a ratchet wheel connected with each shaft, a pawl for operating the ratchet wheel on each winding roller, a link having a longitudinal slot for receiving the shaft of the display roller, pawl arms journaled on the display roller shaft and extending at an angle to each other, a pawl on each arm, 75 said pawls being oppositely arranged for moving the ratchet wheel in opposite directions, a connection between each pawl and the link for alternatively moving the pawls into and out of operative position when the link is moved transversely of the shaft, 80 means connected with the pawls of the winding rollers for moving them in opposite directions to alternatively engage and disengage them from the respective ratchet wheels, and a common means engaging the links and the said pawl moving means for 85 operating them simultaneously.

6. In a device of the character specified, a pair of winding rollers and a display roller, a strip having station designations winding on the winding rollers and passing over the display roller, a ratchet wheel connected 90 with each roller, a pawl for operating the ratchet wheel of each winding roller, a pair of oppositely arranged pawls for moving the ratchet wheel of the display roller in opposite directions, a link arranged transversely 95 of the display roller, and mounted for longitudinal sliding movement, a connection between each of the pawls of the display roller and the link for simultaneously engaging one pawl with the ratchet wheel and disengaging the other, means for moving the pawls of the winding rollers in opposite directions, and a common operating means for the link and the said means.

WILLIAM BUFORD HILL.
